UNITED STATES PATENT OFFICE.

TONJES A. BOTH, OF STRATFORD, CONNECTICUT, ASSIGNOR TO THE CONNECTICUT ELECTRIC MANUFACTURING COMPANY, OF BRIDGEPORT, CONNECTICUT, A CORPORATION OF CONNECTICUT.

DESIGN FOR A CURRENT TAP.

Application filed September 7, 1927. Serial No. 28,320. Term of patent 14 years.

To all whom it may concern:

Be it known that I, TONJES A. BOTH, a citizen of the United States, residing at Stratford, county of Fairfield, State of Connecticut, have invented a new, original, and ornamental Design for a Current Tap, of which the following is a specification, reference being had to the accompanying drawing, forming part thereof.

Fig. 1 is a perspective view of a current tap, showing my new design.

Fig. 2 is a side elevation thereof looking from the right of Fig. 1, and

Fig. 3 is an end view looking toward the bottom of Figs. 1 and 2.

I claim:

The ornamental design for a current tap substantially as shown.

TONJES A. BOTH.
